COMPOSITION ROOF COVERING

Alexander Ritter, Rahway, N. J., assignor to
 Barber Asphalt Corporation, Barber, N. J., a
 corporation of New Jersey

Application September 17, 1940, Serial No. 357,077

8 Claims.

(Cl. 108—7)

This invention relates to a composition roof covering and, more particularly, to composition shingles of novel characteristics per se and in combination as laid for the formation of a roof.

The roof covering or shingle in accordance with this invention is characterized by a novel form and structure such that when laid in courses with other identical shingles, it will provide a maximum of coverage, will not curl at the corners, or at the weather edges, will in the aggregate present an artistic and pleasing appearance, will be easy to lay rapidly and accurately, will require a minimum of nails and, at the same time, will lend itself to cutting from a strip without waste dependent upon the particular embodiment of the invention which may be chosen.

In general, the roof covering according to this invention will be flexible and will be formed of any suitable material, as, for example, bitumen impregnated and coated felt, with or without a surface coating of granular material. Other equivalent or desired material may be used.

The individual elements or shingles will be of a form in general adapting them to be laid according to the so-called "Dutch lap" method.

The individual elements or shingles will be characterized by a general quadrilateral form, with, however, the weather edge portion formed to include offset portions terminating at one side edge; and having the corner formed at the juncture of the weather edge with the opposite side edge turned under to form a locking means. The turned under corner may be so formed as to itself form a locking means for the shingle, or it may serve as a support for locking means, and will be referred to as carrying locking means.

The side edges of the shingle may be perpendicular to the normal lines of the weather edge, or they may be formed on angular lines, as will appear more in detail hereinafter.

When the individual elements or shingles are laid in combination, they will respectively be nailed adjacent opposite corners respectively adjacent to the turned under corner. And the turned under corner, or means supported thereby, will be engaged with an adjacent shingle in the same course at a point adjacent to one of its securing nails, and also with an underlying shingle in the preceding course at a point adjacent to one of its securing nails.

Having now indicated in a general way the nature and purpose of this invention, I will proceed to a detailed description of a plurality of embodiment thereof with reference to the accompanying drawings, in which:

Figure 1 is a plan view of a shingle according to this invention.

Figure 2 is a plan view of an assembly of a plurality of shingles of the form shown in Figure 1.

Figure 3 shows detail of the assembly shown in Figure 2.

Figure 4 is a plan view of a modified form of shingle according to this invention.

Figure 5 is a plan view of an assembly of a plurality of shingles of the form shown in Figure 4.

Figure 6 shows a detail of the assembly shown in Figure 5.

Figure 7 is a plan view, partly broken away, of a pair of shingles of modified form according to this invention in assembled relation.

Figure 8 is a plan view of a portion of a strip of material with the outline of a plurality of shingles of the form shown in Figure 7 laid out thereon and exemplifying the cutting of the shingles from a strip.

Figure 9 is a plan view of a plurality of shingles of a modified form in assembled relation.

Referring now more particularly to Figures 1-3, *a* indicates a flexible composition shingle having opposite parallel side edges *b*, *b'*, a top edge *c* and a weather edge. The weather edge comprises the portion *d* and offset inwardly therefrom, on line *e*, the portion *f*, which terminates at the side edge *b'*.

The corner portion of the shingle formed by the juncture of the side edge *b* and the weather edge portion *d* is turned under on the line *h*, forming a triangular tab *g* from material wholly within the body of the shingle. The tab *g* will desirably be of the form of an equilateral triangle and supports a locking member *i*. The locking member, *i* may be formed by a strip of metal of a length to extend beyond the side edge *b* and weather edge portion *d*; and may be secured to the corner portion *g*, to lie between it and the under side of the shingle *a*, by any convenient means, as, for example, prongs extending from the locking member, or rivets.

The offset weather edge portion *f* is offset, on the line *e*, from the weather edge portion *d* a distance about equal to the length of the fold line or base *h* of the turned under corner portion *g*. In other words, the length of the offset line *e* and its angularity is about the same as the length and angularity of the line *h*. The weather edge portions *d* and *f* are in parallelism.

As has been noted, the side edges *b*, *b'* are parallel and in the form shown in Figure 1 perpendicular to the weather edges *d* and *f*, respectively, and to the top edge. The offset line *e*

extends at an angle of about 45° with respect to the side edges and forms angles of about 225° and 135° , respectively, with the weather edge portions d and f . Desirably the weather edge portions d and f differ in length by the portion of d which forms a side of tab g when the tab is turned under.

When a plurality of shingles of the form shown in Figure 1 are laid, by the so-called "Dutch lap" method, on a roof deck, the structure and effect shown in Figures 2 and 3 is obtained and in which variously j indicates a starter course and k , k indicate successive courses formed with a plurality of shingles a .

It will be noted, more particularly by reference to Figure 3, that the shingles in courses k are lapped with respect to one another in each course and also in adjacent courses, the succeeding courses being overlapped with shingles in the next preceding course. The shingles in the several courses are nailed as at x at opposite corners, which are adjacent to the turned under corner.

As the shingles are laid it will be observed by reference to Figure 3 that the edge portions of the side edge portions of shingles in each course overlie or lap on adjacent shingles, while the weather portion of shingles in successive courses overlie or laps on the upper portion of shingles in the preceding course. The overlapping in the courses and in successive courses results in the formation of a corner between an overlapping shingle, as 1, in one course and an overlapped shingle, as 2, in the next succeeding course, into which the turned under tab g of the next shingle, as 3, in the succeeding course fits and at once controls the amount of overlap of the side edge portion of shingle 3 over shingle 2 and the amount of overlap of the weather edge portions of shingle 3 over shingle 1. In the fitting of the tab g , the locking member i secured to the tab is extended under a weather edge portion of the overlapped shingle, as 2, in the same course and under the side edge portion of the overlapped shingle, as 1, in the previous course, the extensions being adjacent to the points of nailing x of the shingles 1 and 2, respectively.

It will now be noted that, by virtue of the length and angularity of the offset line e , the relative lengths of the weather edge portions d and f with the tab g turned under and the overlapping fixed by the tab g , the shingles when laid will present a regular pattern such as is presented by the well known hexagon strip shingle. At the same time the shingles in the same course and in successive courses will be securely locked together in addition to being secured to the roof deck with a minimum of nailing.

Referring now to Figures 4-6 illustrating a modification, it will be noted that the side edges b^2 , b^3 of the shingle a' extend in general at an angle to the top and weather edge portions and that in detail they are formed on a plurality of lines forming in the edges respectively a plurality of angles l , m . At least one of the lines forming a portion n of one of the edges remote from the adjacent weather edge portion is perpendicular to the weather edge portion and opposite to and parallel with a similar line forming a portion n' of the other edge. The tab g is formed as in the modification shown in Figure 1, as are the offset weather edge portions. It will be noted that the portion w of side edge b which

forms an edge of the tab b is perpendicular to the weather edge d .

As will be observed by inspection of Figures 5 and 6, the shingles of Figure 4 are laid in a manner similar to those of Figure 1, the several similar characteristics and the tabs performing the same functions.

In distinction from the shingles of Figure 1, however, the particular conformation of the edges b^2 and b^3 give to the finished roof a different appearance, without loss of their cooperative function with the tabs g due to the opposite parallel portions, which are perpendicular to the weather edges as will be noted from an inspection of Figure 6.

Referring now to Figures 7 and 8, the shingles a'' illustrated are similar to the shingle of Figure 1, though, if desired, they may have the side edge conformation of the shingle shown in Figure 4, but differ therefrom in that the tabs g' are quadrilateral with their free edges o of greater length than the fold lines h and have their end edges extending on lines forming acute angles with the free edges to form ears q , which serve as locks in place of the locking members i of the shingles of Figures 1 and 4. Further difference resides in the offsetting of the upper edge in conformity with the offsetting of the weather edge and the provision of the triangular recess r of the same sizes as are the ears q on the tabs g' in the upper edge. The recesses r act as accurate lap guides to properly position the shingles to be locked by the ears q on tabs g' , due to the similarity in size of the recesses and ears.

Referring more particularly to Figure 8, there is shown the layout for cutting the shingles of Figure 7 from a strip S without waste, the shingles being cut from a single or double width strip. From an inspection of Figure 8, it will be noted that in cutting out one of the ears q of each tab g , a recess r is formed.

In the shingles a'' the offsetting and relation between offset line e and fold lines h is as in the shingles of Figures 1 and 4.

Referring to Figure 9, the shingles a''' are formed as is the shingle of Figure 1 and differ therefrom, though their sides may be formed as in the shingle of Figure 4, in that their weather edges are doubly offset on lines h , h' , the offset lines being, however, in the same relation to the tab fold lines as in the shingles of Figures 1, 4 and 7; and it being noted that but one tab g is provided at the corner of the shingle.

What I claim and desire to protect by Letters Patent is:

1. A flexible shingle adapted to be laid by the "Dutch lap" method comprising a body having a top edge, side edges, a weather edge comprising portions offset on a line out of the vertical with respect to the weather edge and a folded under tab, carrying locking means, located at a corner of the shingle adjacent one of the offset portions of the weather edge, the fold line of the tab extending at an angle to the adjacent portion of the weather edge and being of about the same length and angularity as the line of offset between the weather portions.

2. A flexible shingle adapted to be laid by the "Dutch lap" method comprising a body having a top edge, side edges, a weather edge comprising offset portions, and a folded under triangular tab carrying locking means, located at and formed by turning under a corner of the shingle

adjacent one of the offset portions forming the weather edge, and the offset portions forming the weather edge being of different lengths.

3. A flexible shingle adapted to be laid by the "Dutch lap" method comprising a body having a top edge, side edges, a weather edge comprising offset portions, and a folded under tab carrying locking means, located at a corner of the shingle adjacent one of the offset portions forming the weather edge, and the side edges extending generally on lines oblique with respect to the offset portions forming the weather edge portions but including opposite parallel portions on lines perpendicular to the weather edge portions.

4. A flexible shingle adapted to be laid by the "Dutch lap" method comprising a body having a top edge, side edges, a weather edge comprising portions offset on a line out of the vertical with respect to the weather edge, and a folded under tab carrying locking means, located at a corner of the shingle adjacent one of the offset portions forming the weather edge, the fold line of the tab extending at an angle of 45° to the adjacent weather edge portion.

5. A flexible shingle adapted to be laid by the "Dutch lap" method comprising a body having a top edge, side edges, a weather edge comprising offset portions extending substantially in parallelism, and a triangular tab carrying locking means formed by folding under a corner portion of the body adjacent to one of the offset portions forming the weather edge on a line extending at an angle to the offset portion adjacent to the turned under corner portion, the vertical distance between the apex and base of the tab being approximately equal to the vertical

distance between the offset portions forming the weather edge.

6. A flexible shingle adapted to be laid by the "Dutch lap" method comprising a body having a top edge, side edges, a weather edge comprising offset portions, and a tab carrying locking means, said tab being formed by folding under a corner portion of the body adjacent one of the offset portions forming the weather edge on a line extending at an angle to the portion of the weather edge adjacent to the turned under corner portion.

7. A flexible shingle adapted to be laid by the "Dutch lap" method comprising a body having a top edge, side edges, a weather edge comprising offset portions, and a tab, said tab being formed by folding under a corner portion of the body adjacent one of the offset portions forming the weather edge on a line extending at an angle to the portion of the weather edge adjacent to the turned under corner portion, and a locking bar secured to said tab and extending beyond the free edges thereof in substantial parallelism with the fold line of the tab.

8. A flexible shingle adapted to be laid by the "Dutch lap" method comprising a body having a top edge, side edges, a weather edge comprising offset portions, and a tab, said tab being formed by folding under a corner portion of the body adjacent one of the offset portions forming the weather edge on a line extending at an angle to the portion of the weather edge adjacent to the turned under corner portion, said tab having its free edge opposite to said fold line of greater length than said fold line.

ALEXANDER RITTER.
